DES. 1958

John Stephenson, of New York, N.Y.

Letters Patent No. 1958-Dated June 14, 1864.

Design for a Pedestal for R.R. Cars.

The schedule referred to in these Letters Patent and making part of the same.

To all whom it may concern:

It is known that I, John Stephenson, of the City, County and State of New York have invented or produced a new and original design for a Pedestal for Railroad Cars, and I do hereby declare that the following is a full, clear and exact description of the same, reference being had to the accompanying drawings, making a part of this specification, in which

Figure 1 is a perspective view of my design.

Figure 2, a central horizontal section of the same.

Figure 3 a plan or top view of the same.

Similar letters of reference indicate like parts in the several figures.

This invention relates to a new and original design for Pedestals in which the axle boxes of a car are fitted.

A is an upright flange at the front edge of a horizontal plate B, which forms the top of the pedestal, and C represents four pedestal plates, two of which are at the front and two at the rear of plate B. These plates have each an elliptical opening a, in them and the inner edges of the two front plates C are provided each with a flange b, projecting forward while the top, bottom, and outer edges are provided with a bead c, the outer lower parts of said plates being rounded, as shown clearly in figure 1, at c'.

DES. 1958

2

The two rear plates C.C. are of the same form as the two front plates, having a bead c. at their outer and lower edges and a flange d. projecting outward at right angles from them near their inner edges.

The front and rear plates are connected at their lower ends by horizontal plates I. hollowed out at their inner edges as shown at e.

I claim as new and desire to secure by Letters Patent

The configuration of the parts herein shown and described to form a new and original design for a pedestal for rail road cars.
